UNITED STATES PATENT OFFICE.

ARTEMUS N. HADLEY, OF INDIANAPOLIS, INDIANA.

TRACTION-WHEEL.

1,109,985:

Specification of Letters Patent.

Patented Sept. 8, 1914.

Original application filed August 12, 1910, Serial No. 576,822. Divided and this application filed April 5, 1911. Serial No. 619,001.

To all whom it may concern:

Be it known that I, ARTEMUS N. HADLEY, a citizen of the United States, residing at Indianapolis, in the county of Marion and

State of Indiana, have invented a new and useful Traction-Wheel, of which the following is a specification, reference being had to the accompanying drawings, and to the letters and figures of reference marked thereon.

This invention relates to driving wheels for portable agricultural engines of the type that is adapted for use in fields for drawing plows, cultivators, or other agricultural implements, or to operate on highways or other roads, not only in self propulsion, but for hauling vehicles or portable machinery from place to place, the invention having reference particularly to driving wheels having adjustable and movable adhesion-increasers.

An engine having the improved driving wheels is illustrated in my pending application for Letters Patent, Serial No. 576,822, filed August 12, 1910, from which the present application for Letters Patent is divided out.

The primary object of the present invention is to provide an improved driving wheel especially adapted for use on relatively soft ground and adapted to afford the maximum adhesive force without being retarded on account of sticky soil.

Another object is to provide improved adhesion-increasers, and adjustable operating apparatus therefor that will be adapted to be reliable under varying conditions of operation.

With the above-mentioned and minor objects in view, the invention consists in an improved driving wheel provided with improved adhesion-increasers that are projectable through the rim of the wheel, and improved mechanism for varying the extent of the downward projection and also for varying the extent of projection of the adhesion-increasers forwardly or rearwardly relatively to the periphery of the wheel; and the invention consists further in the parts, and combinations and arrangements of parts, as hereinafter particularly described and claimed.

Referring to the drawings, Figure 1 is a top plan of a portable engine illustrating the peculiar purposes of the improved driving wheels; Fig. 2, a side elevation of one of the driving-wheels; Fig. 3, a vertical section on the line A A in Fig. 1; Fig. 4, a fragmentary section on the plane of the line B B in Fig. 3; Fig. 5, a fragmentary section on the plane of the line C C in Fig. 3; Fig. 6, a fragmentary section on the plane of the line D D in Fig. 1; Fig. 7, a side elevation of a sectional collar or hub employed in connection with the adhesion increasers; Fig. 8, a perspective view of one of the lugs for holding the parts of the collar together; Fig. 9, an elevation of one part of the sectional collar; and Fig. 10, a fragmentary sectional elevation on the plane of the line E E in Fig. 6.

Similar reference characters in the different figures of the drawings indicate corresponding elements or features of construction herein referred to.

In order to clearly illustrate the adaptability of the improved driving wheels for the purposes intended and to clearly show the relation of the wheels to the engine frame, the more essential features of the engine are herein briefly illustrated and described, said engine comprising a frame suitably composed of longitudinal beams, 1, 1', two end members, 2, 2', two transverse beams, 3, 3', and similar transverse beams, 4, 4', secured to the longitudinal beams, and other transverse members 5, 6, 7, secured also to the longitudinal beams. The lateral portions of the frame are each provided with a downwardly extending pedestal comprising each a pair of members 8 and 8', having a plate 9 secured thereto, the plate 9 having a reinforcing plate 10 thereon, another plate 11 being secured to the pedestal members and having a relatively thick reinforcing plate 12 secured thereto. The plates 9, 10, 11, 12, are suitably apertured to receive an axle 13 or 13', there being two axles of identical construction employed. Each axle has a collar 14 thereon, preferably integral therewith, in the periphery of which is a suitable number of sockets 15. The sockets are adapted to receive an oper-

ating bar for turning the axle adjustably and for holding it when adjusted until secured tightly in the desired position, one end portion of each axle being mounted in a 5 pedestal so as to be adjustable rotatably therein, and the collar 14 is in contact with the plate 10, there preferably being a washer 16 on the axle in contact with the plate 12. Each axle has a threaded end portion 17 on 10 which is a nut 18 that is seated against the washer for securing the axle tightly in the pedestal when adjusted. Each axle has an off-set portion 19 between its ends, being formed between the collar 14 and one end 15 portion of the axle, so that the axle is substantially the same as a crank-shaft.

A driving wheel is provided for each axle and each wheel comprises a hub which preferably consists of two sections 20 and 20', 20 the hub being mounted rotatively on the axle between the collar 14 and the off-set portion or crank, and a web portion comprising preferably two parts 21 and 21', is secured to the hub and has a rim thereon preferably 25 composed of two parts 22 and 22' suitably secured together. The rim has an inwardly extending flange 23 on its outer edge. A hub 24 is mounted rotatively on the outer end of the axle and has a disk 25 thereon 30 which is connected detachably to the flange 23, the disk preferably being detachable from the hub. Each wheel, as will be seen 35 is hollow and adapted to be used on soft ground, the face of the rim being sufficiently broad to sustain the weight of the machine, the webs or disks excluding the soil from the interior of the wheels. Each driving-wheel has a suitable number of apertures or 40 slots 26 in its rim in each of which a blade 27 is arranged movably, each blade preferably having a suitable number of strengthening ribs 28 thereon. Each blade has a suitable shank 29 on opposite sides of which are trunnions 30, 30'.

45 In order to control the blades, which constitute adhesion-increasers, a suitable collar or hub is provided which comprises two parts 31 and 31' that are separable on a plane at right angles to the axle, each part 50 being composed of two pieces, as 31" in Fig. 9, having apertures 32 therein to receive the trunnions and provided with recesses 33 in which are sockets 34 to receive lugs 35 which are provided that have projections 36 and 55' adapted to be inserted in the sockets for securing the two pieces of each part together, the pieces having also bolt holes 37 therein to receive bolts 38 whereby the two parts of the collar are secured together, the collar being 60 rotative on the off-set portion 19 and provided with opposing wings or lugs 39 and 39' adapted to be engaged by the shanks of the blades for rotating the collar. The apertures into which the trunnions extend

are arranged in a circle about the axis of the 65 off-set portion of the axle concentrically thereto. Two sectional collars 40 and 40' are placed on the off-set portion at the opposite sides of the operating collar to prevent the latter from moving sidewise, the 70 parts of the collars 40 and 40' being connected together by bolts 41.

It will be seen from the foregoing that while the wheel rotates on one axis it carries the blades around another axis, and therefore the blades may be forced beyond the rim of the wheel into the ground while the blades in the opposite side of the wheel are retracted relatively to the wheel. It will be clear also that if the off-set portion 19 be adjusted so as to be below the axis of the main portions of the axle, the blades project downwardly, but will project upwardly if the off-set portion be adjusted so as to be above the said axis, and consequently with 80 the latter arrangement the blades are retracted or disappear from the portions of the rim that are in contact with the roadway. It should be understood also that by readjustment of the axle so that the off-set portion is brought either forward or rearward of the rotative axis of the wheel the extent of movement of the blades into the ground may be controlled to suit conditions and be caused to operate at different angles 85 of inclination to the ground.

The inner side of each driving-wheel has a ring 42 thereon that has internal gear-teeth 43, so as to constitute a relatively large gear-wheel which is provided with lugs 44 whereby it is secured to the driving-wheel. Two driving-shafts 45 and 45' are mounted rotatively in suitable journal boxes 46, 46', secured on the top of the lateral portions of the frame, each shaft having a pinion 47 secured thereto that meshes with the gear-teeth 43. The shafts 45 and 45' are in alignment and their inner ends are connected with suitable differential gearing mounted in a casing 48, the gearing being of any preferred or well known type and provided with a sprocket-wheel 49.

A suitable motor 50 is mounted upon the frame and is provided with a bevel gear wheel 51. A counter-shaft 52 is mounted 115 on the frame rotatively and has a sprocket-wheel 53 secured thereto to which is connected a sprocket-chain 54 that is connected to the sprocket-wheel 49. Two bevel gear-wheels 55 and 55' are connected together and mounted slidingly on a counter-shaft and suitably splined thereto so that either one may be moved into engagement with the gear-wheel 51. A lever 56 is mounted on the frame and adapted to shift and control the 120 wheels 55 and 55', an operating rod 57 being connected to the lever and also to a reversing lever 58 mounted on the frame.

A steering-head 59 is mounted rotatively in the member 5 of the frame, so as to turn on a vertical axis, and it has a stem 60 thereon that is arranged at one side of its own 5 rotative axis, the stem constituting a wheel frame on which steering wheels 61 and 61' are mounted. The steering head has a gear wheel 62 thereon and adjacent thereto is a frame 63 adjustably mounted upon the main 10 frame and supporting a worm 64 which is held in contact with the gear-wheel 62 by a suitable latch 65. Said steering apparatus being fully described in said pending application requires no further description but 15 will be understood as being adapted to enable the operator to guide the engine, or permit the worm 64 to be disconnected from the gear-wheel 62 so that the wheels 61 and 61' may trail and support one end of the frame 20 while steering may be accomplished by means of the driving wheels. The lateral portions of the frame are provided with suitable draft devices 66, 66', and similar devices 67, 67', so that gangs of plows or other 25 implements may be hitched to the engine, which, as will be seen, may be run either forward or backward.

In practical use, the blades 27 being nearly as broad as the face of the wheel-30 rim, sink into the soft ground during rotation of the wheel and prevent the wheel from slipping, the driving wheels being actuated as will be seen by powerful gearing. As the driving-wheels rotate and carry the 35 blades out of the ground the latter are drawn inward so that the soil adhering to them is scraped off by the periphery of the wheel. According to conditions of the ground, the axles may be readjusted so as to 40 bring the off-set portions either forwardly or rearwardly; and especially may this be desired when operating the engine first in one direction and then in the opposite direction, and it will be clear that the adjustments may be such as to vary the extent to 45 which the blades may enter the ground.

Having thus described the invention, what is claimed as new, is—

1. A driving wheel including a hollow 50 cylindrical portion and two webs in the extreme ends of the cylindrical portion, the outer faces of the webs being flush with the ends respectively, a plurality of blades in the cylindrical portion and movable relatively thereto and to various degrees of radial angularity and blade-controlling means inclosed by the cylindrical portion and the webs and connected with and guiding the blades longitudinally and also to 55 various degrees of radial angularity.

2. A driving wheel including a hollow 60 cylindrical portion and two webs in the extreme ends of the cylindrical portion, each web having a hub an axle mounted in the

hubs, a plurality of blades in the cylindrical 65 portion and movable relatively thereto and to various degrees of radial angularity and blade-controlling means inclosed by the cylindrical portion and webs and their hubs and coöperating with the axle and the cylindrical portion independently of the hubs for moving the blades to various degrees of 70 radial angularity.

3. In a traction wheel, the combination of an axle provided with a fixed collar having 75 sockets radially arranged in its periphery, a nut on the axle opposite to and at a distance from the collar, two hubs rotatable on the axle, two plates fixed on the two hubs respectively, and a slotted rim fixed on the 80 two plates, with a frame member receiving the axle between the collar and the nut and rigidly held thereby, blades between said plates extending movably through the slotted rim, and means coöperating with the 85 axle for controlling the movement of the blades.

4. In a traction wheel, the combination of an axle having an off-set portion, two opposing collars rotatably mounted on said 90 off-set portion and having each a plurality of radially arranged lugs thereon extending toward the lugs of the opposite collar, and a plurality of blades having shanks that are pivotally connected to the two collars, a 95 shank being movable between two lugs and against one lug of each collar for rotating the collars, with a hub rotatable on the axle adjacent the off-set portion, and a slotted rim mounted on the hub and guiding the 100 blades.

5. In a traction wheel, the combination of a four-part sectional collar provided with radially extending lugs and having transverse pivot holes therein between the portions of the lugs that are relatively close together, the sections of the collar being secured together, a plurality of blades having shanks provided each with trunnions on opposite sides thereof extending into opposite pivot holes of the collar, an axle having an eccentric portion that is rotatable in the collar, and two guide collars secured on said eccentric portion at opposite sides of said sectional collar, with a hub rotatable on said axle adjacent said eccentric portion, and a slotted rim mounted on the hub and guiding the blades.

6. In a traction engine, the combination with a frame, an axle rotatably mounted in 120 the frame and having an eccentric portion, and means for adjustably securing the axle fixedly to the frame, of two hubs rotatable on the axle at opposite sides of said eccentric portion, two inclosing side plates fixedly secured to the two hubs respectively, a slotted rim fixed to said plates, a collar rotatable on said eccentric portion and hav-

ing lateral lugs thereon, and blades guided in said rim and having shanks pivotally connected to said collar and extending between the lugs to move into contact therewith for 5 rotating said collar.

7. The combination of a wheel comprising a slotted rim, an axle having an off-set portion and also a relatively fixed collar having sockets therein, two wheel hubs rotative on 10 the axle at opposite sides of the off-set portion thereof, one of the hubs being composed of sections secured together and arranged between said off-set portion and said collar, a sectional controlling collar or hub rotative on said off-set portion and having radially arranged lugs thereon, a plurality of blades pivotally connected to the controlling collar or hub to move between the lugs and extending through the slotted rim, and 15 plates extending from the wheel hubs to the ends of the rim.

8. In a wheel, the combination with an axle having an off-set portion, and a collar fixed on the axle at a distance from the 20 off-set portion, of a hub rotatable on the axle between the off-set portion and the collar, a disk-like web connected to the said hub, a rim fixed at one end to said web, a hub rotatable on the axle on the farther 25 side of said off-set portion, and a disk detachably connected to the last-described hub and also to the opposite end of said rim.

9. In a wheel, the combination with an axle having an off-set portion, and a collar fixed on the axle at a distance from the 30 off-set portion, of a hub composed of two sections and rotatably mounted on the axle at one side of the off-set portion opposite the collar, a disk-like web secured to the two 35 sections of said hub, a gear wheel secured to said web, a rim portion fixed at one end to said web and having an inwardly extending flange on its opposite end, a disk secured to said flange, and a hub secured to 40 said disk and rotatably mounted on said axle at the opposite side of the offset portion.

10. In a wheel, the combination with an axle having an off-set portion, two collars 45 secured together and rotatably mounted on said off-set portion, each collar having pivotal apertures therein, two hubs rotatably mounted respectively on the axle at opposite sides of the off-set portion, and a slotted rim connected with said hubs, of a 50 plurality of blades having each a reinforcing rib on each of two opposite sides thereof, the blades and the ribs being movable in the slotted rim, each blade having a shank extending between the two collars and provided with two cylindrical trunnions integral on two opposite sides thereof that 55 extend into pivotal apertures of the two collars.

11. In a traction wheel, the combination 65 of an axle having an offset portion and also a controlling collar spaced apart from said portion, the axle having also a securing device opposite to and at a distance from the collar, two hubs rotatable on the axle on 70 opposite sides of the offset portion, two plates fixed on the two hubs respectively, a slotted rim fixed on the two plates, a frame member adjustably receiving the axle between the collar and the securing device, 75 blades between said plates extending movably through the slotted rim, and devices co-operating with the offset portion of the axle controlling the movement of the blades.

12. In a traction wheel, the combination 80 with an axle having an eccentric portion, two hubs rotatable on the axle on opposite sides of the offset portion, two webs secured to the two hubs respectively, and a rim secured to the webs and having slots therein, 85 of two opposing collars rotatably mounted on the offset portion of the axle and having each a plurality of radially arranged lugs thereon extending toward the lugs of the opposite collar, and a plurality of blades 90 extending through and guided in the slots and having shanks that are pivotally connected to the two collars, each shank between two lugs and movable to one of the two, for rotating the collars. 95

13. In a traction wheel, the combination with an axle having an eccentric portion, and a wheel having two hub portions rotatably mounted on the axle on opposite sides respectively of the eccentric portion and 100 having also a rim provided with slots, of a collar rotatable on the eccentric portion and provided with radially extending lugs and having transverse alining pivot holes therein between the portions of the lugs that are relatively close together, and a plurality of blades movably guided in the slots of the rim and having shanks provided each with pivots on opposite sides thereof extending into adjacent pivot holes of the collar. 105

14. In a traction wheel, the combination with an axle having an eccentric portion, and an adjusting collar fixed on the axle at a distance from the eccentric portion, of a wheel comprising two hubs rotatable on the 110 axle on opposite sides of the eccentric portion, one of the hubs being composed of sections and arranged between the eccentric portion and the collar, two plates extending from the two hubs respectively, a slotted rim connected to the two plates, a controlling collar rotative on the eccentric portion of the axle and having radially arranged lugs thereon, and a plurality of blades pivotally connected to the controlling collar to move between the lugs and extending through the slotted rim. 115

15. In a traction wheel, the combination

- with an axle having an eccentrical portion, and a collar having two opposite portions and rotatably mounted on the eccentrical portion, of two hubs rotatably mounted
5 on the axle on opposite sides respectively of the eccentrical portion, two webs connected to the two hubs respectively, a slotted rim connected to the two webs, and a plurality of blades having each a reinforcing rib on
10 one side thereof, the blades and the ribs being movable in the slotted rim, each blade having a shank extending between the two portions of the collar and pivotally connected therewith.
- In testimony whereof, I affix my signature in presence of two witnesses.
- ARTEMUS N. HADLEY.
